UNITED STATES PATENT OFFICE.

ROBERT L. WILT, OF CHICAGO, ILLINOIS, ASSIGNOR TO WILT TRUNK COMPANY, OF CHICAGO, ILLINOIS, A CORPORATION OF ILLINOIS.

TRUNK FIXTURE.

Application filed December 11, 1922. Serial No. 606,031.

To all whom it may concern:

Be it known that I, ROBERT L. WILT, a citizen of the United States, residing at Chicago, in the county of Cook and State of Illinois, have invented certain new and useful Improvements in Trunk Fixtures, of which the following is a specification, reference being had to the accompanying drawings, and to the reference characters marked thereon, which form a part of this specification.

This invention relates to improvements in fixtures for model trunks and the like and more particularly to the type set forth and claimed in U. S. Letters Patent No. 1,000,654 dated August 15th, 1911, wherein the lower member of the standard for the clothes hanger supporting extension rod, is provided with a base to rest upon the floor when the fixture is in its extended position.

The object of the invention is to provide means within a trunk compartment to engage said base when the fixture as a whole is within the compartment and to retain the base therein until it is desired to again extend the fixture.

The invention consists in the devices and combination of devices herein illustrated and described and more particularly pointed out in the appended claims.

In the drawing,

Figure 1 illustrates in a perspective view a trunk of the type referred to, with my invention applied thereto.

Figure 2 is a plan view, enlarged, of the lock plate of my invention in position on the floor or bottom of the trunk compartment.

Figure 3 is a central vertical sectional view of the lock plate, with the standard base lowered into the locked position thereon, the section being taken in the plane indicated by the dotted line 3-3 of Figure 1.

Figure 4 is a rear elevation of a portion of the standard base positioned within the lower end of the fixture standard, the latter being shown in vertical section.

Figure 5 is a sectional view of the standard base, showing part of the base and the lower end of the standard in elevation, the section being taken on the plane of dotted line 5-5 of Figure 4.

As shown in these drawings the trunk comprises two open front compartments A and B, suitably hinged together along a

vertical line, as at 1, so as to swing in a horizontal plane and close one upon the other when the trunk is setting upon end.

Within the upper end of a compartment, A, for example is a clothes hanger, supporting fixture or rail 2 upon which a plurality of garments on hangers may be supported, and packed closely together within the compartment, and in which they may be held in packed position by the usual "follow" board 3, or the like. To the outer end of the rail 2, the inner end of a tubular extension rail 4 is pivotally secured, so that said extension rail 4 may lie in a vertical position when not in use (as shown in dotted line in Fig. 1) or may be swung into the horizontal position illustrated, in extension of the hanger supporting rail 2.

The support or standard for the outer end of the extension rail 4 usually comprises three members, a tubular upper member 5, a lower inner member 6 and a base member 7. The tubular upper member 5 is adapted to telescope within the extension 4 and is provided with a hinge 8 so that its major portion may be swung at right angles to the rail 4 as clearly shown in Figure 1. The main part of the inner member 6 extends upwardly into the lower part of the upper tubular member 5 and its lower end is secured in an upward tubular branch 9 of the base member 7. The member 7, usually in the form of an ordinary pipe fitting, is provided with a plurality of spread arms 10, as shown, there being a headed plug 11 on the end of each of the arms 10 to form a bearing therefor. As the bearing 11 and the fitting proper 7 lie in the same plane, a strong, firm support or base is provided which for lack of a better name, I designate as a crow-foot base.

My lock plate as a whole is designated by the letter C, and comprises a body 12 adapted to suitably rest upon and be secured to the inside surface of the bottom 13 of the trunk compartment, as for instance, by lugs 14 and screws 15. The upper surface of the plate C is recessed and shaped as shown, at 16, to form a suitable bearing for the base fitting 7.

The plate C is bored at 17 for a bolt bearing, the bore extending at one end into one of the spaces 16 and terminating at its other end in an apertured shoulder 18.

Within the bore 17 and projecting at one

end through the apertured shoulder 18, is a bolt rod 19. This rod is provided on one end with a handle 20 and on the other end with a bolt 21. The bolt 21 will project out 5 side of the bore 17 when the handle 20 lies in contact with the outer surface 22 of the plate C. The base fitting 7 is provided with a bore or aperture 24 to receive the bolt 21 when the base fitting 7 is positioned 10 upon the plate C.

Within the bore 17 and surrounding the rod 19 is a spring 23, one end of which contacts with the inner end of the bolt 21 and the other end with the shoulder 18. The 15 outer edge of the bolt aperture 24 is somewhat flared as shown at 25, and the end of the bolt 21 is preferably slightly rounded as shown at 26, so that the bolt will readily slip into the aperture. The normal position of the bolt, due to the tension of the spring 23, is that shown in Fig. 2. When the base fitting 7 is placed upon the plate C, the bolt 21 may be manually withdrawn by means of a pull on the handle 20, compressing the spring 23, or it will be forced 25 back into the bore 17 against the tension of the spring 23 by the base fitting 7 as the latter is seated on the plate. In each case, when the base 7 is in place on the plate C, 30 the spring 23 will force the bolt 21 into the aperture 24 and thus hold and lock the two together.

In order to place the various parts of the fixture together and thus lock them to the 35 plate C within the trunk compartment, the base 7 and the member 6 are first raised, the rod 6 sliding into the tubular rod 5 until the top edge or shoulder of the base extension 9 contacts with the lower edge of a 40 sleeve 27 on the upper supporting member 5. This will bring the base 7 a substantial distance above the top level of the base plate C. The member 5 will then be swung at 45 8 and pushed within the extension rod 4, until the top edge of the sleeve 27 contacts with the annular shoulder 28 on the extension 4. The parts will be locked together by the notch hook 29 of the lever 30 engaging the shoulder 31 on the support 5, 50 and also by the pin member 32 of the lever 30 engaging an annular groove or recess 33 in the rod 6. Then the telescoped fixture 4 may be swung vertically until within the 55 compartment with the base 7 above the plate C.

Then the lever 30 will be moved to withdraw the pin 32 from the recess 33 and the base 7 and rod 6 will be moved down until the base rests upon the plate C and is locked 60 thereon by the bolt 21. The fixture will

then be within the compartment A in the position shown in dotted lines in Fig. 1.

To bring the extension 4 into the horizontal position, the bolt 21 is withdrawn, the base 7 and rod 6 raised until the base 65 clears the top of the plate C, whereupon the tubular extension 4 can be swung into extension of the arm 2, the support or standard arms 5 and 6 withdrawn from within the extension 4, the member 5 swung into vertical position about its pivot 8, and then the base 7 will be pulled down until it has a firm rest upon the floor.

My device is simple, fool-proof in that it does not require special instructions to operate, relatively cheap, neat in appearance, and does not require much room, while it is positive in its action and when locked, the fixture is anchored in position within the compartment and the objections to having a movable part therein are avoided.

I claim as my invention:

1. In a receptacle having a clothes hanging compartment, the combination with a suspension device pivotally secured to the top of the compartment of an apertured base for said device provided with three rigid radially-extending supporting arms, a fixture secured to the floor of said compartment and provided with grooves shaped to receive said arms, and means carried by said fixture adapted for movement into the aperture in said base and to detachably secure the latter in position within said fixture.

2. In a receptacle having a clothes hanging compartment, the combination with a suspension device pivotally secured to the top of the compartment of an apertured base for said device provided with three rigid radially-extending supporting arms, a fixture secured to the floor of said compartment and provided with grooves shaped to receive said arms, and means carried by said fixture adapted for movement into the aperture in said base and to detachably secure the latter in position within said fixture, said means comprising a spring-controlled locking bolt extending through a wall of the fixture and into one of said grooves, and positioned for entry into the aperture in said base, when the latter is inserted into the grooves in said fixture.

In testimony that I claim the foregoing as my invention I affix my signature, in the presence of two witnesses.

ROBERT L. WILT
